UNITED STATES PATENT OFFICE.

CHARLES V. SANDERSON, OF STREATOR, ILLINOIS.

COUPON-BOOK.

SPECIFICATION forming part of Letters Patent No. 717,930, dated January 6, 1903.

Application filed October 21, 1901. Serial No. 79,464. (No model.)

To all whom it may concern:

Be it known that I, CHARLES V. SANDERSON, a citizen of the United States, residing at Streator, in the county of Lasalle and State 5 of Illinois, have invented a new and useful Coupon-Book, of which the following is a specification.

This invention relates to coupon-books.

The object of the invention is to present a 10 coupon-book adapted more particularly for use in the ice trade and between the dealer and the purchaser, in the use of which provision is made whereby the purchaser will be enabled at a glance to ascertain the number 15 of pounds of ice still due him from the company and in which at a glance the auditor or bookkeeper of the company will be enabled to know just how many pounds of ice has been purchased.

20 A further object is to present a coupon-book having these features and the additional feature of a guide or self-calculator by which the wagonman will be enabled with rapidity and absolute accuracy to detach from 25 the book coupons representing the amount of ice purchased.

A further object is to present a coupon-book having the above features which shall be exceedingly simple of construction and 30 may be employed by persons of limited education with certainty of results, thereby avoiding mistakes which are liable to occur when mental calculation is required on the 35 part of the dispenser in calculating the number of coupons to be detached to correspond with the amount asked for by the consumer.

With these and other objects in view, as will appear as the nature of the invention is better understood, the same consists in the 40 novel construction and combination of parts of a coupon-book, as will be hereinafter fully described and claimed.

In the accompanying drawings, forming a part of this specification, and in which like 45 numerals of reference indicate corresponding parts, there is illustrated one form of embodiment of the invention, together with a slightly-modified form of one portion thereof, capable of carrying the same into practical operation, it being understood that the

elements therein exhibited may be varied or changed as to shape, proportion, and exact manner of assemblage without departing from the scope of the invention, and in these drawings—

55

Figure 1 is a view in elevation exhibiting the cover of the book spread out flat to display the explanatory matter printed thereon relative to the use of the book. Fig. 2 is a view in longitudinal section, taken through 60 the book when folded up. Fig. 3 is a diagrammatic view exhibiting the guide or self-calculator and the manner in which the same is used. Fig. 4 is a fragmentary detail view of a slightly-modified form of coupon-slip 65 from that shown in Fig. 1. Fig. 5 is a view in perspective of the book partly open.

Referring to the drawings, 1 designates generally the cover of the book, the same comprising a front 2, a back 3, and a flap or leaf 70 4, the cover being foldable into book-like form, as shown in Fig. 2. The front 2 has printed thereon matter setting forth the number of pounds of ice for which the coupons of the book are good, together with the name of 75 the firm, the conditions under which the coupons are to be used, and other matter serving to identify the holder of the book. The back 3 contains printed matter explanatory of the use of the book, and the flap 4 contains 80 directions as to the manner in which the coupon slip or ribbon is to be manipulated when coupons are detached therefrom. The cover and printed matter thereon displayed are merely illustrative of one arrangement 85 that may be employed and is furnished to render clear an understanding of the present invention, it being understood that this printed matter may be varied or changed to suit the requirements of the company issuing the 90 same.

It is to be remarked at this point that while the coupon-book is herein described as applicable for use in the ice trade it is to be understood that it is not to be limited to this 95 employment, as it may be adapted for use in connection with other businesses where its use will be advantageous and still be within the scope of the invention.

Secured to the flap on its rear side and near 100

its upper end is one end of the coupon-slip 5, the same being made of a narrow slip of paper having printed thereon two columns of figures 6 and 7, divided by a heavy line 8 into 5 multiples of five, running from "5" downward to "2,000" in the 6 column and from "5" upward to "2,000" in the 7 column. The left-hand column 6 is provided to enable the purchaser to tell at a glance how many pounds 10 of ice is still due him from the company, and the right-hand column is provided to enable the bookkeeper or auditor at the office of the company issuing the book to ascertain at a 15 glance just how many pounds of ice the consumer has received, and these columns will hereinafter be designated "Amount due" and "Amount received" columns. As herein shown the coupon-slip is made to represent a valuation of two thousand pounds; but it 20 is to be understood that this amount may be indefinitely increased, if desired or if found necessary. At a point near the upper end of the flap is provided a transverse slot 8', through which the free end of the slip is 25 passed, and above the slot is printed directions as to how the slip or ribbon is to be removed from the book. In addition to the printed directions as to how the slip is to be drawn from the book the flap bears on one 30 side and spaced to conform to the divisions on the coupon-slip a guide or self-calculator 9, comprising a column of figures divided into multiples of five, running from "5" to "100," this self-calculator, as before pointed 35 out, being provided to enable the wagonman with absolute accuracy to determine the number of coupons to be torn off for any amount of ice from five pounds to one hundred pounds. Instead of having the two columns of figures 40 6 and 7 divided off into divisions representing multiples of five the same may be divided into divisions representing one and multiples thereof, as shown in Fig. 4, and when this form of slip is used the same rules apply in 45 its employment as in the form of coupon-slip shown in Fig. 1.

To facilitate separation of the coupons from the slip, the lower end of the front may be provided with a metallic tearing or cutting 50 edge 10, (shown in Fig. 1,) this to be of a piece of metal, as a strip of tin, having its ends bent around the sides of the front and pinched there, or it may be held assembled there in any desired manner. While the use 55 of this tearing edge will be of advantage, it is to be understood that the invention is not to be limited to its employment, as it may be dispensed with and the lower end of the front be made to perform this function.

50 The coupon-slip is herein exhibited as being folded upon itself in regular lengths in zigzag order and is held in place between the flap and back by a rubber band or other fastening means brought into engagement with 65 notches 11, formed in the sides of the back and the flap, as shown in Fig. 1. By thus

securing the flap and back together all danger of the coupon-slip working out from between the parts when folded to the position shown in Fig. 2 is obviated, and at the same time the slip will be free to be drawn from the cover.

The manner in which the book is used is as follows: When the book is first purchased the footing of the "Amount due" column will 75 bear two thousand and that of the "Amount received" column five. Now suppose the purchaser desires seventy-five pounds of ice. The wagonman draws down the coupon-slip until the division-line 12, separating "75" 80 and "80," is in alinement with the tearing edge 10, and the slip is then torn off. Now suppose the holder after this purchase desires forty pounds more. Of course this amount will necessitate tearing off eight coupons, and as the division between the coupons is small there is liability of the wagonman making a mistake, and it is under these conditions that the guide or self-calculator comes into play. When the former coupons were 90 torn off, "80" was at the bottom of the "Amount received" column 7. Now to tear off coupons equivalent to forty pounds the wagonman draws down the slip until "80" thereon alines with the "5" on the guide, and 95 by looking at the figure on the slip opposite the "40" on the guide "115" will appear, which will indicate to the wagonman that the coupon-slip is to be torn off on the division-line between "115" and "120," this calculation being clearly exhibited in Fig. 3. The guide or self-calculator is herein shown, as before stated, as divided into multiples of 100 five, running to one hundred, and this will be all that is necessary in ordinary household usages; but it is to be understood that, if desired or found necessary, the scale on the guide may be increased without departing from the scope of the invention.

By the employment of this form of coupon-book the transactions of business between the dealer and purchaser is facilitated, and as a further advantage inherent in this invention the accuracy with which the calculations may be made will render its employment highly advantageous to both dealer and consumer. Furthermore, by the employment of the "Credit" and "Debit" columns of figures, by which terms the columns 6 and 7, respectively, may be entitled, the keeping of accounts between the purchaser and the dealer will be greatly simplified, and the labor of the bookkeeper in keeping such accounts will be reduced to a minimum.

Having thus fully described my invention, 125 what I claim as new, and desire to secure by Letters Patent, is—

A coupon-book comprising a front, back and flap, the latter being provided with a transverse slot and bearing adjacent to one 130 edge a column of figures constituting a guide scale or calculator, and a slip having one end

secured to the back of the flap and its free end passed through the slot, and bearing on its face columns of figures, the designating values of which increase in opposite directions, the arrangement of the figures in the column adjacent to the scale corresponding in order of arrangement or progression thereto.

In testimony that I claim the foregoing as my own I have hereto affixed my signature in the presence of two witnesses.

CHARLES V. SANDERSON.
